ATTORNEY

UNITED STATES PATENT OFFICE

MANUEL J. MEDEIROS, OF SAN JOSE, CALIFORNIA

BUILDING IRON

Application filed October 28, 1929. Serial No. 403,013.

This invention relates to an iron used in building up the wax mold used in the formation of electrolyte plates.

In the performance of this work it is customary to use a pointed hot iron against the surface of which the wax is melted as the tool is moved over the work.

This method of working is highly objectionable because it requires the use of both hands at all times, and it is extremely difficult to follow a given line accurately and at the same time to secure an even flow of melted wax over the point of the iron. Furthermore in this method of working the heated wax may spatter and so disfigure the mold as to necessitate the making of a new one.

It is the object of the present invention to provide a means whereby the wax may be prepared and held in readiness in a suitable liquid condition, and fed on to the point of the iron at such times and in such quantities as the operator may desire, thereby eliminating the difficulties above referred to.

The drawing is a side elevation of one embodiment of my invention, part broken away and part in section.

In this embodiment of my invention the pointed iron 1 is provided with an upstanding annular flange 2 to form a pocket 3, this flange being exteriorly threaded as at 4. In order to increase the capacity of the pocket 3 a member 5 is threaded thereon as shown. Upon the iron 1 is mounted a handle 6.

At 7 I show an outlet port formed in the flange 2 at the base of the pocket 3, the port being formed with a seat at 8. On the seat 8 is seated a valve 9 normally held in a closed position by a spring 10 bearing thereagainst and against a bearing member 11 in which the stem of the valve is mounted. The valve is actuated to an open position by means of a lever 12 pivotally mounted on the handle as at 13 and having its shorter arm engaging a head 14 on valve 9 and its longer arm extending outwardly as at 15 adjacent the grip of the handle 6.

In its practical application a quantity of wax is placed in the pocket 3 where it is maintained in a liquid condition by the

heated iron 1, the said iron being heated in any suitable manner as by gas jets fed through pipes as at 16. As the point of the tool is moved over the work the liquid wax is allowed to feed down over the point of the heated iron in any desirable quantity by manipulation of the valve 9.

It is to be understood, of course, that while I have herein shown and described but one specific embodiment of the invention, changes in form, construction and method of assembly and operation may be made within the scope of the appended claims.

I claim:

1. In a tool of the type set forth, a receptacle for containing a supply of wax, an element having its lower portion formed to deposit fluid wax upon a given surface, and means for heating the receptacle, said lower portion of the element being closed on all of its sides and its lower end and having its opposite end connected to the receptacle, and said receptacle having a valve controlled discharge port for permitting the heated wax to egress therethrough in predetermined quantities and to flow downwardly over the exterior of the lower portion of the element to the given surface.

2. In a tool of the type set forth, a receptacle for containing a supply of wax, an element having a lower portion closed on all sides and ends connected to the receptacle and formed to deposit fluid wax upon a given surface, a handle connected to the receptacle and extending outwardly therefrom at an angle, means for heating the element, said receptacle having a discharge port, a spring pressed slid valve carried by the handle for controlling said discharge port so that melted wax may egress from the receptacle and flow downwardly over the exterior of the element to the given surface, and means to operate the valve carried by the handle.

3. In a tool of the type set forth, an element having a pocket at its top and having a lower portion formed to deposit wax upon a given surface, said lower portion of the element being closed on all sides and both ends, a receptacle connected to the pocket to increase the capacity thereof, and a valve con-

trolled discharge port extending through the pocket and above the upper end of said lower portion of the element so that melted wax may egress from the pocket and flow downwardly over the exterior of the element to the given surface.

4. In a tool of the type set forth, a receptacle for containing a supply of wax, an element connected to the receptacle and having a lower portion closed on all sides and ends and formed to deposit fluid wax upon a given surface, a movable support for the receptacle connected thereto, means for heating the element and receptacle from the exterior thereof, said receptacle having a valve controlled discharge port located above the lower portion of the element so that melted wax may egress from the receptacle in predetermined quantities and flow downwardly over the exterior of the element to the given surface, and a valve disposed exteriorly of the receptacle for controlling the port thereof.

MANUEL J. MEDEIROS.
